ABSTRACT: Floating platform comprising a rigid structure driven into the sea bottom and projecting from the sea surface, and a floating platform freely rotatable and vertically movable with respect to the rigid structure, but restrained thereto in its transverse displacements. The floating platform is of an elongate shape in order to enable a vessel moored thereto to be disposed in accordance with the best strong side wind, the platform being also capable of varying its height relative to the sea surface, in which it can be completely immersed.

FLOATING PLATFORM FOR VESSEL MOORING

The present invention relates to a floating platform for vessel mooring or docking and more particularly a platform for docking and unloading of tankers, oil tankers and the like.

It is an object of this invention to provide a platform wherein its height with respect to the sea surface can be varied in a very simple and rapid manner.

Another object is to provide a platform enabling a rapid and simple docking for vessels thereto and allowing a vessel docked thereto to be oriented according to the best strong side wind, that is to assume at any time the most convenient direction in accordance with the prevailing wind and sea conditions.

A still further object is to provide such a platform that, in case of need, such as where unusually violent storms are encountered, may be largely caused to descent below the sea surface in order to be preserved from the violence of waves and wind.

These and still other objects are attained by a floating platform comprising a stationary structure, and end of which is driven into the sea bottom and the other end of which projects from the sea surface and a first platform carrying a plurality of bitts for vessel mooring, a plurality of watertight hollow bodies being fast therewith, such bodies being at least partially immersed in the sea water and provided with valves and pumps selectively operable for introducing into and discharging sea water from said hollow bodies, means being provided for avoiding transverse displacements of said first platform relative to the stationary structure and allowing the free vertical displacement and rotation about the fixed vertical axis of the first platform with respect to said stationary structure.

In order that the structure and features of the floating platform be more clearly understood, an embodiment thereof will now be disclosed by mere way of nonrestrictive example, reference being made to the accompanying drawing in which:

FIG. 1 is a diagrammatic vertical cross section of the platform according to line I-I of FIG. 2;

FIG. 2 is a diagrammatic plan view of the floating platform;

FIG. 3 is an enlarged detail view of the platform as taken on line III-III of FIG. 1; and

FIGS. 4 and 5 are diagrammatic plan views showing two different positions as assumed by a vessel moored to the platform under the action of the wind and waves.

Reference is now made first to FIGS. 1-3 wherein a floating platform is shown and comprises a stationary platform or structure formed of a plurality of poles 1, the lower end of which is driven into the sea bottom and the upper end of which projects from the sea surface, as particularly shown in FIG. 2.

A fixed platform 3 is fast with the upper end of poles 1, said platform 3 being at a greater height than the sea surface and of a circular plan shape (FIG. 2), whereas a rigid wall 4 is provided about and fast with poles 1, the outer surface of said wall 4 being cylindrical and of a circular cross section with vertical axis coincident with the axis of platform 3. The cylindrical wall 4 extends above the sea surface at surface of platform 3 and below the sea surface, as shown in FIG. 1. A hole is provided centrally of platform 3, from which hole there projects the end 5 of a sea line 6 extending below the sea surface to the coast in a substantially conventional manner and provided by sturdy metal pipes. Sea line 6 and end 5 thereof are interconnected by a double ball joint 7 enabling said end 5 to perform slight oscillations relative to a horizontal plane. It can also be seen that sea line end 5 is provided with a set of inlets 8 through which oil or other liquid can be introduced into sea line 6.

A platform 9 is anchored to the described stationary structure, said platform 9 having a circular hole through which the described stationary structure extends.

Platform 9 is formed of a sturdy metal reticular structure (FIG. 1) and carries a plurality of rolling members 11 freely

rotatably supported about their own axes 12, such axes being fast with platform 9. The rolling members can be made of steel coated with thick rubber, but preferably comprise tires mounted on rims of the type being used by motor vehicles (see the detail of FIG. 3), all about the cylindrical wall 4 there being provided a plurality of supporting shafts 12 for rolling members 11, on each shaft there being also mounted a plurality of rolling members which are superimposed to one another.

Rolling members 11 abut the cylindrical surface of wall 4 and can roll thereabout and axially slide therealong so as to allow the free rotation of platform 9 and the vertical displacement thereof relative to the stationary structure, but preventing platform 9 from transversely moving with respect to said stationary structure.

Six sets of watertight hollow bodies are fast with the reticular platform structure, each hollow body 13 comprising a hollow rounded-bottom cylinder, as particularly seen in FIG. 1. Hollow bodies 13 are provided with valves and connected to pumps, for simplicity not shown in the drawings as being of an evident construction, which are operable to introduce into and discharge sea water from said hollow bodies. When the sea water is fully ejected from hollow bodies 13, platform 9 is lifted relative to the sea surface, while when water is made to penetrate into said hollow bodies 13 the platform is lowered on the sea surface, which platform 9 may also be fully immersed into the sea; thus the platform height can simply and readily accommodate the height of the vessel moored thereto and platform 9 can also be preserved from the violence of the wind and waves, by causing it to immerse into the sea in case of specially violent storms.

A propeller connected to a driving motor is fast with at least one of the sets of hollow bodies 13, the propeller being immersed in the sea water and suitable, when operated, to impart a rotary motion of platform 9 about the vertical axis of platform 3. Also the propeller and driving motor herein mentioned have not been shown for simplicity in the drawing, since the construction and operation thereof is clearly evident and the disclosure thereof is not deemed necessary for understanding the present invention.

Finally, from FIGS. 1 and 2 it can be noted that platform 9 is of elongate shape and has a straight side from which a plurality of fenders 14 project, a vessel mooring to the platform will bear against said fenders 14.

From FIGS. 1 and 2 it can also be seen that the axis of rotation for platform 9, i.e. the axis of platform 3, is more adjacent to one end of platform 9 than to the other end thereof, or in other terms it may be stated that the structure of platform 9 is eccentric with respect to its axis of rotation.

Adjacent the ends of the elongate platform bitts 15 are provided and further bitts 16 are provided adjacent the free end of an extension laterally extending from the platform.

Assuming that an oil tanker has to moor to the platform, such a vessel can approach the platform from any direction, particularly under the most suitable strong wind side, that is according to the most favorable conditions of wind and sea; when in proximity of the floating platform, the vessel 18 (FIGS. 4 and 5) will throw the ropes 17 on the bitts of platform 9, approaching thereto until bearing a side thereof against the fenders 14.

The vessel will substantially assume the position as schematically shown in FIGS. 4 and 5. Since the platform is rotatable about a vertical axis, said platform will readily assume the most convenient orientation with respect to the vessel under the pull action of the ropes between the vessel and the platform bitts, i.e. the platform will alone dispose itself with said fenders 14 facing the vessel side.

Mooring operations being completed, the oil tanker is readily connected to the inlets 8 of sea line 6 by pipes which may be made entirely of metal and jointed and through which the oil can be easily and very rapidly unloaded from the oil tanker through the sea line under conditions of extreme reliability, high rapidity and minimum load losses because of the connection between the oil tanker and sea line, such a connection occurring through metal pipes which may have a large diameter.

During vessel mooring to the platform, should the conditions of the wind and sea exert a pressure on the vessel side, or exert a force which has been shown by a series of horizontal arrows parallel to one another in FIGS. 4 and 5, the vessel along with the movable platform 9 would rotate about the vertical axis of platform 3 tending to assume the position as shown in FIG. 5, wherein the resistance against the wind and sea force is minimum, thus minimizing the hazards of vessel unmooring from the platform.

It is apparent that the stationary structure of the floating platform has to be so dimensioned as to resist the approaching impact due to the mooring of a loaded tanker, such an impact being damped by the rolling members 11 which, as above mentioned, are of resilient material. It is also apparent that the level of platform 9 can be easily and continuously suited to the level of the vessel moored thereto.

Thus with the structure of the invention the several posts 1 together with the cylinder 4 and the top wall 3 form a stationary means having an upright axis about which the platform 9 is free to turn. The platform 9 together with the parts connected thereto forms a mooring means to which a vessel, such as the vessel 18 may be moored, so that with the invention the mooring means 9 is free to turn about the axis formed by the stationary means. The mooring means 9 is elongated so that the turning axis thereof is situated closer to the right end of the mooring means 9 than the left end thereof, as viewed in FIG. 2. Moreover, the situation of the bitts 16 on the lateral extension of the mooring means 9 enables the ropes 17 to extend from the vessel to the side of the turning axis of the mooring means 9 opposite from that where the vessel is located. Therefore, when the wind acts on the vessel in the manner shown in FIG. 4, the entire structure is free to turn to the position shown in FIG. 5 where the wind blows in the same direction as illustrated in FIG. 4. However, in the position of FIG. 5, the pulling of the ropes 17 on the bitts 16 provides a counter-clockwise force, as viewed in FIG. 5, opposing the tendency of the wind to turn the platform means 9 in a clockwise direction, as viewed in FIG. 5, so that in this way the vessel and the platform means 9 will automatically assume a stabilized position where the resistance against the wind and the force of the sea is at a minimum, so as to minimize the possibility of unmooring of the vessel from the platform means.

I claim:

1. In a vessel-mooring structure, stationary means having an upright axis, and floating platform means to which a vessel is to be moored, said platform means having an elongated con-

figuration and terminating in a pair of opposed ends, and said stationary means being operatively connected with said platform means between said opposed ends thereof but substantially nearer to one of the said ends than the other for guiding said platform means for free rotary movement about said upright axis while restraining said platform means substantially against movement transversely to said axis, and said platform means coacting with said stationary means for automatically assuming, particularly when a vessel is moored to said platform means, a position where resistance against wind and sea forces is substantially at a minimum, said elongated platform means having on one side of said stationary means an elongated exposed uninterrupted side extending longitudinally between the ends of said platform means and to which a vessel 10 may be moored, said platform means including a lateral extension terminating outwardly beyond said stationary means at a side thereof opposed from the location of said elongated uninterrupted side of said platform means.

2. The combination of claim 1 and wherein said platform means includes bitts situated adjacent the opposed ends of said platform means as well as at an outer end region of said lateral extension of said platform means.

3. In a vessel-mooring structure, stationary means having an upright axis, and floating platform means to which a vessel is 20 to be moored, said platform means having an elongated configuration and terminating in a pair of opposed ends, and said stationary means being operatively connected with said platform means between said opposed ends thereof but substantially nearer to one of said ends than the other for guiding said 25 platform means for free rotary movement about said upright axis while restraining said platform means substantially against movement transversely to said axis, and said platform means coacting with said stationary means for automatically assuming, particularly when a vessel is moored to said platform 30 means, a position where resistance against wind and sea forces is substantially at a minimum, said stationary means including an outer cylindrical wall having an axis coinciding with said upright axis and said platform means surrounding said outer cylindrical wall of said stationary means and carrying a plurality of shafts 35 parallel to said upright axis, said plurality of shafts supporting for free rotary movement tires which engage said cylindrical wall for providing the free turning of said platform means with respect to said stationary means while restraining said platform means against radial movement with respect to said upright axis and absorbing radial forces.
